UNITED STATES PATENT OFFICE.

FRANCIS W. CARPENTER, OF HARRISON, NEW YORK.

TOY.

SPECIFICATION forming part of Letters Patent No. 298,446, dated May 13, 1884.

Application filed February 1, 1884. (No model.)

To all whom it may concern:

Be it known that I, FRANCIS W. CARPENTER, of Harrison, in the county of Westchester and State of New York, have invented an Improvement in Toys, of which the following is a specification.

In Letters Patent No. 274,270, heretofore granted to me, a toy horse is shown, and a revolving wheel with a crank-pin acting to swing or move the horse as the toy is drawn along. In Letters Patent No. 104,370, also granted to me, there is a toy cart of cast metal.

My present invention relates to a figure adapted to be used with a toy animal or vehicle, the figure having a base upon which it can be supported, there being a pin and opening for holding the figure when in place, and a removable rest with a notch is also used for receiving the toy figure, so that it may have the appearance of being seated when placed against the rest. By this construction the same figure that is of a shape to stand up straight is also adapted to use with a representation of a seat.

25 In the drawings, Figure 1 is a side view, partially in section, of a toy horse, the frame and wheels for the same, and a toy figure actuated by the crank or pin that also moves the horse or animal. Fig. 2 is a plan of the same, 30 and Fig. 3 represents the toy figure as placed at the seat in a cart or other toy vehicle.

The frame A is supported upon the wheels B C, and it is adapted to be drawn along by a cord attached to the cross-piece d. At 35 e are standards for the cross-bar or pivot f, upon which the horse G, or other toy animal, is placed, and between the wheels B is the crank-pin h, preferably covered with a tube of india-rubber. This crank-pin, as it revolves with the wheels, comes into contact with the hind leg of the animal and gives to the same a rocking motion. The bar J is pivoted at i, and it rests at the back end upon the cross-bar K, and it is lifted by the crank-pin h, as it is revolved with the wheels, as 40 aforesaid. The toy figure L may be made to represent a child or person with one hand raised to the hat, so as to form a loop, around which the rein or cord m is passed; or any 45 other form of figure may be used, such as one with the arm extended and an opening between the thumb and finger. There is a base, n, to the figure, and it is connected to the bar J, or other support, by a pin, p, entering an 50 opening. Usually the pin will be upon the

bar J and the opening in the base n; but the parts may be reversed. There is a support, o, representing a seat. This is notched, so as to allow the figure to be placed into said notch, so that when stood into its place the figure looks as if it were seated; but when removed from its place the figure will stand upright upon its base n. This arrangement admits of using the same figure to represent a person seated when placed in the support 60 or seat, or standing when the support or seat is removed. The support or seat o, Fig. 1, is represented as provided with a pin to enter a hole in the end of the lever-arm. When this figure is stood upon the cart, as represented in Fig. 3, the same is supported in the manner before described. In cases where the base n of the figure can be placed with one edge against a support—such as the side of the toy cart—the opening in the base n for the pin p 70 75 may be a notch, so as to be cast more easily.

The notch or opening can be formed either in the figure or in the rest or support for the figure.

I claim as my invention—

1. The combination, with a wheeled toy having a rest, of a toy figure, the figure and rest being connected by one part having a notch to receive the other part, substantially as set forth.

2. The combination, with a wheeled toy, of a figure and a pin and socket, by means of which the parts are connected, substantially as set forth.

3. The combination, with a toy figure, of a notched rest, a base, a pin, and an opening for receiving the pin, substantially as set forth.

4. A toy figure, in combination with the pivoted bar, a frame or support, the wheels, and the crank-pin or lifter, substantially as 95 set forth.

5. A toy figure, in combination with a pivoted lever, a pivoted animal, the frame or support, the wheels, and the crank-pin or lifter, substantially as set forth.

6. In a wheeled toy, the combination, with a pivoted animal, of a wheel and a crank-pin or projection acting upon the animal to swing the same, and a figure connected with such toy, substantially as set forth.

Signed by me this 31st day of January, A. D. 100 105 1884.
